UNITED STATES PATENT OFFICE.

CLARENCE R. LININGER, OF CHICAGO, ILLINOIS.

HIGH-TENSION SWITCH.

1,172,470.

Specification of Letters Patent. Patented Feb. 22, 1916.

Application filed May 14, 1915. Serial No. 28,074.

To all whom it may concern:

Be it known that I, CLARENCE R. LININGER, a citizen of the United States of America, residing at Chicago, county of Cook, State of Illinois, have invented a new and useful 5 High-Tension Switch, of which the following is a specification.

This invention relates to an electrical switch or apparatus for opening and closing electrical high voltage transmission circuits, the object of which invention being to provide 10 a device of this nature adapted for use in connection with either single or multi-phase circuits. For instance, where it is necessary to sectionalize an electrical transmission line, or to open or close a branch circuit at the point of intersection with the main electrical transmission line, or for the 15 protection of any other electrical equipment that may be operated from such electrical high voltage transmission lines.

Another object of the invention is to provide 20 a resilient but permanent seat or stop for one of the contacting terminals of the switch.

Owing to the recent progress and development 25 of high tensioned transmission circuits, it has become necessary to provide proper devices that can be operated under all natural or weather conditions.

Therefore, it is another object of the invention to provide an improved switch that can be operated under all weather conditions, and will attain and maintain positive 35 contacting between the contacting terminals or stationary and movable switch members.

Another object of the invention is the provision 40 of such improved contacting terminals or switch members, that when brought into coöperation, one will tend to cut or break the ice or sleet from the other, and even in rainy weather one contacting terminal will tend to scrape against the other, thereby shedding the water and the like 45 from the other terminal. Such freezing of the water, to form ice or sleet, or the snow that may adhere to such terminal contacts will be easily and quickly ruptured by the revoluble action of one of the contacting 50 terminals.

In practical fields the details of construction may necessitate alterations, falling within the scope of what is claimed.

The invention comprises further features 55 and combination of parts, as hereinafter set forth, shown in the drawings and claimed.

In the drawings:—Figure 1 is a view in perspective of the improved electrical switch or apparatus constructed in accordance with the invention. Fig. 2 is an enlarged side elevation of a portion of the electrical switch. Fig. 3 is a top plan view of the structure shown in Fig. 2. Fig. 4 is a vertical sectional view through Fig. 2. Fig. 5 is an enlarged detail view of a portion of 60 one of the guard guide cutting contact terminal arms at the free end or extremity of the movable switch member. Fig. 6 is a detail view in cross section on line 6—6 of Fig. 3, showing the two guard or guide cutting contacting terminal arms, as scraping against opposite sides of a stationary contacting terminal arm. Fig. 7 is an enlarged detail view of the means for supporting the stationary contacting terminal or arm upon 70 a porcelain support. Fig. 8 is a detail view showing the key pin 18 for securing the ear 19 of the post or standard 20 to the shaft 12. 75

Referring more especially to the drawings, 1 designates a channel iron base, 80 designed for supporting the various elements of the electrical switch or apparatus. Secured by bolts or other suitable means 2 to one end portion of the channel iron base is the base plate 3 of a winged metallic standard 4, the upper portion of which terminates in a threaded extension 5, which is threaded into a suitable insulator member 6, which may be constructed of any suitable material, such as glass, porcelain or the like. 85 This insulator is provided with a plurality of projecting tiers varying in diameters from the lowermost tier to the uppermost, acting to shed the water and the like from the lower portion of the standard 4. This 90 insulator at its upper extremity is constructed with a head 7, between which and the uppermost shedding tier an annular groove 8 is formed, the purpose of which will appear later. 95

Secured to the other end of the channel base by means of bolts or other suitable means, 9, is a supporting bracket 10 having ears 11, revolvably mounted in bearings of 100 which is a rocking shaft 12. On one end of the shaft an arm 13 is keyed, as shown at 14, and to the arm the bifurcated end 15 of the operating rod 16 is pivoted, as shown at 17. Fastened to the other end of the rocking shaft, by virtue of a suitable key pin 110 18 is an ear 19 of the metallic post or standard 20, the upper end of which terminates

in a threaded extension 21 similar to the extension 5, and which is threaded into an insulator 22 similar in construction to the insulator 6, which is likewise provided with 5 a head 23 and groove 24.

Carried by each of the insulators above its respective head is a cap plate 25, which is provided with three radially and downwardly extending integral arms 26. These arms 26 10 at their lower portions extend inwardly toward the groove of the uppermost portion of the insulator so as to engage said groove, as shown clearly in Figs. 1, 2 and 4. The lower portions of the arms 26 are integrally 15 connected by the ring sections 27, which are constructed with enlargements 28 having receiving sockets 29. These enlargements 28 are located adjacent two of the diametrically oppositely disposed arms 26, as shown 20 clearly. The lower inturned portions of the arms 26 and the ring sections 27 engage one-half of the groove, and to hold said arms in such positions and the cap plates 25 rigidly in place a semi-annular ring section 30 is 25 provided, which engages the other half of the groove. The ends of the semi-annular ring section are received in the sockets 29, and are secured therein by any suitable means, such as soldering and the like, as 30 shown at 31. By virtue of this construction it is to be observed that the cap plate 25 of each of the insulators is held firmly or rigidly in position, thereby affording a rigid support.

35 Secured by suitable screws 32 upon the cap plate 25 of the insulator 22 is a supporting bracket 33, the upper lug 34 of which has an opening 35, in which a switch member or arm 36 is adjustably secured by the set screw 37. The supporting bracket 33 has an extension 39 provided with a binding screw 40, to which one of the leads or wires of any suitable high tensioned or voltage transmission circuit may be connected.

45 To the cap plate 25 of the insulator 6 a bracket plate 41 is secured by suitable screws 42. The bracket plate 41 has an extension 43 provided with a binding screw 44, to which the other side of the line or circuit 50 may be connected. The bracket plate 41 is formed with an enlargement 45 having an opening 46, in which the laterally extending end 47 of the yieldable contact terminal or arm 48 is secured in any suitable manner.

55 This contacting terminal as will be noted, is supported stationarily, but at the same time its vertical portion is yieldable. This vertical portion 49 is formed into a single coil 50, which is likewise slightly yieldable, and beyond the coil 50, the vertical portion 49 terminates in the yieldable contacting stationarily supported terminal or arm proper 51. It is clearly evident that just beyond 60 the coil 50 this yieldable contacting terminal proper is curved slightly toward the switch

member or arm 36, as shown at 52, then curves in the opposite direction as shown at 53.

Threaded or otherwise secured at 54 to the free end of the tubular switch member or 70 arm 36 is a sleeve 55, which is bifurcated as shown at 56. In bearings of the forks 57 between which the bifurcation 56 is formed, a suitable shaft pin 58 is mounted, thereby forming a journal bearing for the grooved 75 contacting wheel terminal 59. Formed integral with and extending laterally in opposite directions from the arms or forks 57 are lugs 60 having sockets 61, in which the downwardly extending portions 62 of the cutting 80 guard or guide contacting terminals or arms 63 are secured in any suitable manner (not shown), however, for instance, by virtue of soldering or otherwise.

It will be observed that in plan view the 85 terminals or arms 63 rise upwardly and laterally and toward each other, then upwardly and outwardly from each other, thereby forming a space between such terminals or arms, which is contracted substantially at 90 its central portion and of a greater width at both ends. It will be observed that in plan view the contacting wheel terminal is so disposed relative to the contacting terminals or arms 63, that the groove in said wheel is 95 substantially corresponding to the contracted portion of the space between the arms or terminals 63, so that when the switch member or arm 36 is thrown in the position shown in Fig. 1, the arms or terminals 100 63 will act to draw the contacting terminal 51 toward the groove in the wheel, thereby maintaining a sure contact of the parts. Moreover, it is to be observed that the upper portion of the single coil 50 is aligned 105 vertically with the groove in the contacting wheel, which not only affords a yieldable support for the contacting wheel and the switch arm or member 36, but which, owing to the weight or pressure of the member 36 110 on the coil 50, causes the contacting terminal 51 to bear firmly in the groove of the contacting wheel. The harder the pressure upon the switch member or arm 36, more secure becomes the contact between the members 51 and the wheel 59. When the switch member or arm 36 is thrown into the position shown in Fig. 1, the contacting wheel or member 59 first engages the curved portion 53 substantially at the point indicated 115 at 65, and as the switch member or arm 36 moves downwardly toward the coil 50, the wheel rolls upon the contact member 51, thereby rupturing the sleet and ice on the contacting member 51 thereby causing a true 120 contact of the engaging parts, and as pressure is exerted upon the switch member or arm 36, thereby causing the contacting wheel to engage the coil (which tends to cause the contacting member 51 to lean to- 125 130

ward the coil) the contact between the engaging parts becomes greater. Furthermore, as this engagement is produced, the contacting arms or terminals 63 likewise scrape against the curved portion 53. In other words, the arms or terminals 63 owing to their cutting edges 66 strip or cut the ice and sleet from the curved part 53 of the terminal 51 thereby insuring the closing of the electric circuit, in which the electrical switch or apparatus may be located. No matter what quantity of ice and sleet may form upon these contacting parts, the closing of the circuit is assured. In other words, where any two of the engaging or contacting parts fail to close the circuit, other contacting or engaging parts will close the circuit, and vice versa.

When electrical installation is installed, whether on the interior or the exterior of a plant, preferably exteriorly, the current on one side of the line is conveyed to the apparatus through the binding member 44 over the lead 68, from any suitable source. Thence the current carries through the contacting member 51, the contacting wheel 59 and the arms 63, through the switch member or arm 36 to the other side of the line over the lead or wire 70, to various devices (not shown) for the proper operation of the same and to maintain a continuous electrical circuit.

The invention having been set forth, what is claimed as new and useful is:

1. In an electrical switch, a stationary contact member, but yieldable incident to pressure thereon, a movable contact member comprising a member revolvable in its action incident to engaging the stationary contact member, and combined additional contact members and ice and sleet removing devices carried by the movable contact member for engagement with the stationary contact member, and a contacting coil for insuring engagement of the contacting parts incident to pressure upon the coil, said coil constituting a support for the revolvable member and acting to cause the stationary but yieldable contact to lean against said revolvable member.

2. In an electrical switch, a stationary member having multiple electrical contact parts, a movable switch member having multiple contact terminals to coöperate with said parts, one of the multiple electrical contact parts of the stationary member constituting means to draw the stationary member toward one of the multiple contact terminals, said contact parts causing the draw-

ing of the stationary member acting as a support for the movable switch member.

3. In an electrical switch, stationary supporting means, a contact member on said means and being yieldable incident to pressure thereon, said stationary contact member being formed into a contact coil and a curved arm beyond the coil, a movable switch member having a sleeve upon one end provided with forks, a revoluble contact member journaled in said forms to engage and receive said arm and cause the arm to yield incident to the pressure of the revoluble member thereon, opposing contacting terminals carried by said forks engaging upon and scraping against opposite sides of said arm, said coil acting as a support yieldable incident to pressure thereon by the movable switch member and acting as a contact received by the revoluble contact member.

4. In a high tension switch, an electric movable switch member having a contact terminal, a stationary member having an electrical contact part, and provided with a support for the terminal, which support draws said part toward the terminal holding the terminal against the support.

5. In a high tension switch, an electric movable switch member having a revoluble contact terminal, a stationary member having an electrical contact part yieldable toward the terminal when in contact therewith, said member having an electrical support below and offset from said part to support the terminal, which support draws said part toward and against and holds the terminal against the support.

6. In a high tension switch, an electric movable switch member having a revoluble contact terminal, a stationary member consisting of a single element constructed to form a tensioning coil and terminating therebeyond in an electrical contact part yieldable toward the terminal, when in contact therewith, said coil being below and offset from said part forming a crotch to receive the terminal; the coil acting as a support for the terminal, and its tensioning action drawing said part toward and against the terminal holding the same against the support.

In the presence of two witnesses, my signature is hereto affixed

CLARENCE R. LININGER.
